UNITED STATES PATENT OFFICE

166,904

PROTECTIVE SUIT

Thomas A. Bridges, Jersey City, N. J.

Application July 17, 1951, Serial No. 15,910

Term of patent 14 years

(Cl. D3—17)

To all whom it may concern:

Be it known that I, Thomas A. Bridges, a citizen of the United States, residing at Jersey City, county of Hudson and State of New Jersey, have invented a new, original, and ornamental Design for a Protective Suit, of which the following is a specification, reference being had to the accompanying drawings, forming a part hereof.

Fig. 1 is a side perspective view of a protective suit showing my new design;

Fig. 2 is a similar view thereof as it appears in partially opened position with the head covering thrown back;

Fig. 3 is a rear elevational view of the protective suit shown in Fig. 1; and

Fig. 4 is a front elevational view thereof.

I claim:

The ornamental design for a protective suit, substantially as shown and described.

THOMAS A. BRIDGES.
